CONTROL PANEL FOR RADIO OR SIMILAR ARTICLE

Robert D. Bessier, 4606 W. 78th Terrace,
Prairie Village, Kans.

Filed June 5, 1963, Ser. No. 75,231

Term of patent 14 years

(Cl. D56—4)

FIG. 1

FIG. 3

FIG. 2

FIG. 4

FIG. 5

FIGURE 1 is a perspective view of a control panel for a radio or similar article showing my new design;
FIGURE 2 is an enlarged front elevational view;
FIGURE 3 is an enlarged side elevational view;
FIGURE 4 is an enlarged top plan view; and
FIGURE 5 is an enlarged bottom plan view.

The dominant features of my design reside in the portions shown in full lines with the fragmentary broken line showing a radio cabinet being for illustrative purposes only.

I claim:

The ornamental design for a control panel for radio or similar article, as shown and described.
